UNITED STATES PATENT OFFICE.

JOHN M. FELLOWS, OF BURLINGTON, INDIANA.

FENCE-POST.

1,202,694.

Specification of Letters Patent.

Patented Oct. 24, 1916.

Original application filed June 30, 1915, Serial No. 37,216. Divided and this application filed May 16, 1916. Serial No. 97,830.

To all whom it may concern:

Be it known that I, JOHN M. FELLOWS, a citizen of the United States, and a resident of Burlington, in the county of Carroll and State of Indiana, have invented a new and Improved Fence-Post, of which the following is a full, clear, and exact description.

This invention relates to fence posts and has particular reference to metallic posts having novel means for locking line wires thereto.

Among the objects of the invention is to provide a fence post having improved means for securing the longitudinal or main line wires thereto in such a manner that they cannot become accidentally disconnected, the fastening means, however, being such that the operator may connect or disconnect the wires readily when desired.

20 The subject matter of this application is disclosed in and was divided from a previous application for metal fence posts, filed June 30, 1915, Serial No. 37,216, and allowed December 27, 1915.

25 With the foregoing and other objects in view the invention consists in the arrangement and combination of parts hereinafter described and claimed, and while the invention is not restricted to the exact details of 30 construction disclosed or suggested herein, still for the purpose of illustrating a practical embodiment thereof reference is had to the accompanying drawings, in which like reference characters designate the same 35 parts in the several views, and in which—

Figure 1 is a front elevation of the principal parts of a fence post embodying my improvements; Fig. 2 is a side elevation of the same, the wires being in section and 40 other parts being broken away; Fig. 3 is a side elevation of that part of the post that directly receives the wires; Fig. 4 is a perspective view of one of the filler members serving to lock a wire in place; and Fig. 5 is a horizontal section on the line 5—5 of Fig. 1.

Referring now more particularly to the drawings, I show a fence post structure comprising a main post 10 of any suitable 50 angular formation to provide maximum strength and rigidity in proportion to its mass. This post is provided with a vertical rib 11 which may be either integral therewith or, as in the previous application, may 55 constitute a vertically adjustable extension

member for the main post or base 10, the same being adapted to be locked in adjusted position by keys or set screws 12 of any suitable construction operating through the wings 13 of the extension and the web of 60 the main post. For the present consideration, however, the principal feature of this part of the post lies in the wire seats 14 formed rearwardly and downwardly from the front edge of the rib. That is to say, 65 each of the seats has a horizontal portion terminating at its rear end in a vertical downwardly extending portion constituting at its lower end a seat for the wire W. The seat and the slot leading thereto are only 70 slightly larger than the diameter of the wire, although as to this feature I do not wish to be unnecessarily limited. The post rib or extension may be provided with any suitable number of these wire seats, and they 75 may be spaced according to the spacing for the wires or they may be made more numerous so that wires may be placed closer or farther apart as may be desired for any particular purpose of the fence. Preferably I 80 provide the notches or wire seats in large numbers so that the wires may be placed at varying distances apart.

After the fence posts have been set and the extension, if any, has been adjusted and 85 locked in adjusted position, the wires are strung and spaced as above suggested, the seats 14 for the wires serving to hold the wires temporarily from displacement. The operator then proceeds to lock the wires in 90 place using for this purpose, first, a filler 15 for each wire seat, said filler being, as shown in Fig. 4, in the nature of a small metal block having a rounded or cylindrical face at its lower end to embrace the upper portion of the wire and the block otherwise filling the vertical space above the wire in the wire seat. The operator places these several blocks in the several wire seats for each post. The thickness or width of each block is preferably the same as the thickness of the rib 95 11. A keeper 16, preferably formed in U-shape of sheet metal, is slipped directly over the rib, the side portions of the keeper embracing the sides of the rib and the blocks 100 15. The keeper is notched at its rear edges at 17 so as to straddle the several wires. The notches 17 are spaced apart according to the spacing of the wire seats of the post. The keeper is then locked to the rib by 110

means of removable transverse fasteners 18 passing through registering holes 19 and 20 formed in the keeper and the rib respectively. These fasteners 18 prevent the displacement or movement of the keeper, and the keeper holds the blocks 15 from displacement, and hence the wires are held positively in their seats.

I claim:

- 10 1. In a fence post construction, the combination of a rigid member comprising a vertical rib having open front notches, the notches terminating at their lower ends in wire seats below the open fronts, filler blocks inserted in the rear portions of the notches to hold the wires down in their several seats, and a U-shaped member coöperating with the rib to hold said filler blocks from move-

ment in any direction, said keeper having straight horizontal notches formed to receive the wires when slipped rearwardly over the rib and being imperforate on opposite sides of the upper ends of the rib notches and filler blocks.

- 20 2. In a fence post, the combination of a vertical rib having notches extending rearwardly from the front edge thereof and thence downwardly forming wire seats, a filler block for each wire seated in a wire seat, each filler block having its lower end 30 concaved to embrace the upper portion of the wire, a keeper embracing the rib and filler blocks and having notches to receive the wires, and means to detachably secure the keeper to the rib.

JOHN M. FELLOWS.
